UNITED STATES PATENT OFFICE.

CARL PAULI, OF SOUND BEACH, CONNECTICUT, ASSIGNOR TO GARWOOD COMPANY, OF GARWOOD, NEW JERSEY, A CORPORATION OF NEW JERSEY.

MECHANICAL MOVEMENT.

1,252,485.

Specification of Letters Patent.

Patented Jan. 8, 1918.

Application filed October 4, 1916. Serial No. 123,615.

To all whom it may concern:

Be it known that I, CARL PAULI, a citizen of the United States, residing in Sound Beach, in the county of Fairfield and State 5 of Connecticut, have invented certain new and useful Improvements in Mechanical Movements, of which the following is a specification.

This invention relates to a mechanical 10 movement in general, such as illustrated in my copending application Serial No. 51187, filed September 17, 1915, and more particularly to centrifugal hammers. The subject-matter forming the basic feature of the 15 present specification has been divided out of the aforesaid copending application.

The present invention particularly contemplates the provision of a centrifugal hammer which encircles a rotatable driving 20 member and is provided with a guiding member surrounding said centrifugal hammer.

The present invention further contemplates the structural features which particularly adapt the present invention for 25 use on percussion drills or dental pluggers.

These and other features, capabilities and 30 advantages of the invention will appear from the subjoined detail description of specific embodiments thereof, illustrated in the accompanying drawings in which—

Figure 1 is an end elevation of one embodiment in which a guiding member and disk member constitute an open housing for 35 the hammer.

Fig. 2 is a side elevation of the embodiment illustrated in Fig. 1, with the hammer in drill striking position.

Fig. 3 is a side elevational view similar 40 to Fig. 2, with the hammer out of drill striking position.

Fig. 4 is an end elevation of another embodiment, in which the hammer is disposed in a closed housing.

Fig. 5 is a side elevation of still another embodiment similar to that illustrated in Fig. 4, and in which the anchoring member for the hammer guiding member is flattened out on one side.

Fig. 6 is a side elevation, similar to Fig. 5, of still another embodiment in which the hammer spring is dispensed with.

In the embodiment illustrated in Figs. 1, 2, and 3, there is provided an actuating shaft 50 which may be driven by any suitable

source of power, not shown. On the shaft 10 is fixedly secured the member 11 which comprises a disk member 12 through which the shaft 10 extends, and the hammer guide member such as the crescent-shaped member 13 extending laterally from said disk 12 and parallel to said shaft 10, the disk member 12 constituting an anchoring member for the guiding member 13. On the shaft 10, and inside of the guiding member 13 is 60 mounted the hammer 14 which is annular in form and encircles the shaft 10, the guiding member 13 maintaining the hammer eccentric to said shaft 10.

The horns 15 of the guiding member 13 70 preferably are of sufficient extent so that the distance between their free ends is less than the diameter of the outer periphery of the hammer 14, whereby such horns may serve as an anchoring member for the hammer member 14, especially to prevent such hammer from contacting with the shaft 10.

To form a cushion for the hammer 14 and also to flexibly maintain the hammer 14 in its outermost position, the flat spring 16 is 80 provided, such spring being disposed in the recess 17 formed in the bottom of the guiding member 13.

When the aforesaid arrangement is to be used for drills and the like, a tool holder 85 18 may be provided with its hammer engaging end 19 disposed approximately in line with the outer periphery of the guiding member 13. The outer periphery of the hammer 14 will be such relative to its thickness, the outer periphery of the guiding member 13, and the thickness of the shaft 10, that it may project from between the horns 15 a considerable distance beyond the outer periphery of the guiding member 13 90 and thus engage the end portion 19 whenever the opening between the horns 15 are disposed adjacent to the end portion 19.

The embodiment illustrated in Fig. 4 comprises a shaft 10', a member 11' embracing 100 a disk portion 12' and a guiding member 13', a hammer 14', a spring 16', and tool holder 18', all substantially identical with the parts bearing like reference characters, not primed, in Figs. 1, 2 and 3. In the present embodiment, a disk member 20 is provided through which extends the shaft 10' and which is secured to the guiding member 13' by any suitable means, such as the screws 21 illustrated in the present instance. The outer 110

periphery of the disk portion 20 is preferably of the same dimension as the outer periphery of the disk portion 12' and alines therewith.

- 5 The embodiment illustrated in Fig. 5 comprises a shaft 10^a, a hammer 14^a, a spring 16^a, and a tool holder 18^a, all substantially identical with the parts bearing like reference characters, that are primed, in Fig. 4.
- 10 In the present embodiment a member 11^a, embracing a disk portion 12^a and a guiding member 13^a, is provided in which the guiding member 13^a is substantially identical with the guiding member 13' of the embodiment illustrated in Fig. 4, and in which the disk portion 12^a has one end cut away so that the disk portion 12^a is flat adjacent to the horns 15^a of the guiding member 13^a, such flat side being designated 22 and extending from one horn 15^a to the other horn 15^a.

The embodiment illustrated in Fig. 6 comprises a shaft 10^b, a member 11^b embracing a disk portion 12^b and a guiding portion 13^b, a hammer 14^b, and a tool holder 18^b, all substantially identical with the parts bearing like reference characters that have the exponent "a" in Fig. 5. In the present embodiment a spring, such as the spring 16^a of the embodiment illustrated in Fig. 5, is dispensed with. The inner periphery of the guiding member 13^b is preferably such, relative to the outer periphery of the hammer 14^b, that the hammer 14^b will always be maintained eccentric to the shaft 10^b.

It is obvious that various changes and modifications may be made to the details of construction without departing from the general spirit of the invention.

40 I claim:

1. The combination with a rotatable shaft, of an annular-hammer encircling said shaft and loosely mounted thereon; and means disposed externally of said hammer for holding and guiding it eccentric to the shaft.
2. The combination with a rotatable shaft, of an annular hammer encircling said shaft, a crescent-shaped member disposed externally of said hammer for guiding said hammer, the horns on said crescent-shaped member being disposed a sufficient distance from one another to permit the hammer to project therefrom into striking position.
3. The combination with a rotatable shaft, of an annular hammer encircling said shaft, a crescent-shaped member for guiding said hammer, and means for anchoring said crescent-shaped member externally of said hammer and to said shaft, the horns of said crescent-shaped member being spaced a sufficient distance from one another to permit the hammer to project therefrom into striking position.
4. The combination with a rotatable shaft, of an annular hammer encircling said shaft,

a crescent-shaped member for guiding said hammer, means for anchoring said crescent-shaped member externally of said hammer and to said shaft, the horns of said crescent-shaped member being spaced a sufficient distance from one another to permit the hammer to project therefrom into striking position, there being a recess in the bottom of said crescent-shaped member, and a flat spring disposed therein and engaging said hammer to flexibly maintain the hammer in projected position.

5. The combination with a rotatable shaft, of an annular hammer encircling said shaft, means for guiding said hammer eccentric to said shaft, a disk member secured to said shaft from which said guiding means extends laterally, and a second disk member through which said shaft extends and secured to said guiding means so that said disk members and guiding means will form a housing with one another in which the hammer is floatably mounted.

6. In a mechanical movement, a revolute drive shaft; a single-piece cylindrical floating hammer-member loosely carried by the shaft having its axis parallel with the axis of the drive-shaft; a guiding-member housing open at a portion of the periphery to allow of partial protrusion of the periphery of the floating hammer-member; and a spring normally forcing such hammer member into the protruding position.

7. In a mechanical movement, a drive-shaft; a housing of substantially crescent shape secured to and rotating with said shaft; a floating cylindrical hammer-member located within the crescent-shaped-member which crescent-shaped-member maintains said floating hammer-member in a position eccentric to the shaft; and a spring disposed in the crescent-shaped-member, normally forcing the cylindrical floating-hammer-member out through the peripheral orifice between the horns of the crescent of the housing to the limit of its play therein, so as to constantly maintain the floating hammer-member axis eccentric to the axis of rotation of the shaft and crescent-shaped-member.

8. In a mechanical movement, the combination with a rotatable shaft; of an annular hammer-member encircling and loosely mounted on said shaft; and a member fixed to said shaft and guiding the annular member eccentric to the shaft.

9. In a mechanical movement, the combination with a rotatable shaft; of an annular hammer-member encircling and loosely mounted thereon; and a crescent-shaped member fixed to said shaft and guiding the annular member eccentric to the shaft.

10. In a mechanical movement, a revolute drive-shaft; a single-piece cylindrical floating hammer-member loosely carried by

the shaft having its axis parallel with the axis of the drive-shaft; a guiding member housing open at a portion of the periphery to allow of partial protrusion of the periphery of the floating hammer-member and means normally forcing such hammer-member into the protruding position.

11. In a mechanical movement, a drive-shaft; a housing of substantially crescent shape secured to and rotating with said shaft; an annular floating hammer-member mounted upon the drive-shaft but unsecured thereto, located within the crescent-shaped-member, which crescent-shaped-member 15 maintains said floating-member in a position eccentric to the drive-shaft; and a spring disposed in the crescent-shaped-member, normally forcing the annular floating-member out through the peripheral orifice between the horns of the crescent to the limit 20 of its play therein, so as to constantly main-

tain the floating hammer-member axis eccentric to the axis of rotation of the shaft and crescent-shaped-member.

12. In a mechanical movement, a drive-shaft; a housing of substantially crescent shape secured to and rotating with said shaft; a floating cylindrical hammer-member located within the crescent-shaped-member which crescent-shaped-member maintains said floating hammer-member in a position eccentric to the shaft and protruding peripherally from between the horns of the crescent of the housing to the limit of its play therein, so as to constantly maintain 35 the floating hammer-member axis eccentric to the axis of rotation of the shaft and crescent-shaped-housing.
